UNITED STATES PATENT OFFICE.

GEORGE K. HUNDLEY, OF INDIANAPOLIS, INDIANA.

DESIGN FOR AN ILLUMINATING GLOBE.

Application filed March 15, 1926. Serial No. 16,918. Term of patent 3½ years.

To all whom it may concern:

Be it known that I, GEORGE K. HUNDLEY, a citizen of the United States of America, a resident of the city of Indianapolis, county of Marion, and State of Indiana, have invented a new, original, and ornamental Design for Illuminating Globe, of which the following is a specification, reference being had to the accompanying drawing, forming a part thereof.

The figure is a front elevation of a lighting fixture showing the illuminating globe in full lines.

I claim:

The ornamental design for an illuminating globe substantially as shown.

GEORGE K. HUNDLEY.
